UNITED STATES PATENT OFFICE.

BYERS W. KADEL, JOHN A. PILCHER, ROBERT H. PERSINGER, AND H. WALLACE REYNOLDS, OF ROANOKE, VIRGINIA.

DRAFT ATTACHMENT FOR RAILWAY-CARS.

1,325,156.

Specification of Letters Patent. Patented Dec. 16, 1919.

Application filed November 14, 1914. Serial No. 872,213.

To all whom it may concern:

Be it known that we, BYERS W. KADEL, JOHN A. PILCHER, ROBERT H. PERSINGER, and H. WALLACE REYNOLDS, citizens of the United States, residing at Roanoke, in the county of Roanoke and State of Virginia, have invented certain new and useful Improvements in Draft Attachments for Railway-Cars, of which the following is a specification.

This invention relates to draft appliances for railway cars and its object is to provide an improvement in the draft or coupler yoke as will be herein set forth, and it consists in the formation, combination and arrangement of elements as will be herein described and claimed.

In the accompanying drawings Figure 1 is a partial vertical, longitudinal section of a car having our improvements thereon, and Fig. 2 is a plan view, partly in section of the same. Fig. 3 is a horizontal sectional view through the back end of the coupler yoke, taken on the line A—B, Fig. 1. Fig. 4 is a broken side elevational view of a slightly altered form of coupler yoke.

Referring now to these drawings 1 represents the center sills of a car, 2 the end sill, and 3 the coupler striking plate. The coupler 4 is supported by a customary carry iron 5 and is disposed between the center sills 1.

Our invention is especially intended for use with those forms of coupler yokes which consist of U-shaped straps of metal between the center sills, the open end of the U engaging and connecting with the butt end 6 of the coupler 4. This U-shaped strap or yoke 7 is customarily riveted or keyed to the butt end of the coupler, or has sliding engagement therewith. In the device as we use it, it is necessary that the coupler be slidably attached to the yoke 7, and to perform this and at the same time form a secure fastening the open ends of the U are provided with the customary lugs 8 adapted to position in front of the enlarged portion of the butt end of the coupler and be engaged thereby in pulling. Embracing the open ends of the U is a solid ring or thimble 9 which is secured at the top and the bottom to the legs of the U by means of bolts or rivets 10. The coupler has slideable engagement with the yoke 7 in buffering and the thimble 9 prevents the legs of the U from opening when the coupler engages the lugs 8 in pulling.

Within the opening of the coupler yoke and disposed immediately behind the butt end of the coupler is the customary front follower plate 11 which forms a beam between the two center sills, resting against the follower stops 12. The draft gear 13 is likewise inserted in the opening of the coupler yoke in the customary manner, between the front and rear follower plates.

The rear follower plate 14, however, is made rigid with the curved back end of the yoke 7, it being shown in Figs. 1, 2 and 3, as being formed of two parts, the front portion 15 having a flat face at its front to accommodate the face of the draft gear. The rear portion 16 of this follower has a flat face at its back which corresponds with a similar face on a back stop 17, this back stop being disposed between the center sills of the car.

The two portions of the rear follower 14 are secured together and to the rear end of the coupler yoke by any suitable means such as the rivet 18.

The rear follower thus forms a solid block between the draft gear and the back stop when buffering and is not at this time subject to any bending stresses, but to pure compression only. To those familiar with car construction the advantages of this construction will appear, as the absence of the customary rear follower stops and the use instead of our heavy back stop will prevent the buckling of the sills that now takes place under severe buffering.

At the same time, the rear follower plate not being called on to function as a beam between the customary rear follower stops it may be made much lighter as there will be no bending stresses to take care of.

It will be evident that we require sliding engagement of the coupler and coupler yoke in buffering as at this time the coupler simply slides back in the yoke, which remains stationary, the rear end of said yoke serving as before stated, as a dead block or compression member.

In pulling, our device operates in the identical manner as the present well known devices of this character, the front follower abutting the stops 12 and forming a beam between the sills, the draft gear being compressed between the front and rear follower plates.

It will be evident that various sliding

forms of attachment of the coupler yoke to the coupler might be used and also that the rear follower plate might be made in a variety of forms.

5 In Fig. 4 we show an alternate form of this rear follower, the same being here made of a single piece and the metal of the coupler yoke itself serving to abut the back stop 17, which is made with a curved face to accommodate the curved end of the yoke.

10 In addition to the advantages already enumerated our device as described forms a most sturdy and rugged construction with a minimum number of parts and particularly a minimum number of moving parts. It may be assembled as a single unit and placed on old cars or new, many of the standard parts as now used being retained, and but slight alterations being required to 15 old equipment in order to use our new device. It may also be used with all of the present Master Car Builders' standard couplers.

20 Having thus described our invention, what 25 we claim is:

1. In a draft rigging for railway cars, the combination with a vertically arranged yoke, of a coupler slidably connected thereto, a centrally arranged stop adapted to hold 25 the yoke from rearward movement, a draft gear within the said yoke, a follower for said gear, and means connected to said follower and embracing said yoke and adapted to form a compression member between said 30 follower and the stop on the inward movement of the coupler from normal.

35 2. In a draft rigging for railway cars, the combination with a pair of spaced draft sills, of a coupler, a vertically arranged yoke, 40 means for connecting said coupler and yoke

and adapted to permit relative movement therebetween, a draft gear within the said yoke, followers for the same, vertically arranged stops connected to the said sills and coacting with one of the said followers, a 45 back stop bridging the space between the said sills, and means connected to the other follower and adapted to normally contact with the forward face of the back stop.

3. In a draft rigging for railway cars, the 50 combination with vertically arranged yoke and cushioning means, of a follower for the said cushioning means, said follower contacting with the rear inner face of the said yoke, and means connected to the said follower and inclosing said yoke and adapted to prevent relative movement between the 55 said yoke and the said follower.

4. In a draft rigging for railway cars, the combination with the draft sills, of a yoke, 60 means connected to the sills and bridging the space between the same and adapted to hold the yoke from rearward movement, a draft gear, a two-part follower, one part whereof is adapted to contact with the said 65 gear, the other part of the said follower being adapted to embrace the yoke and to contact with the aforesaid means, and means for connecting the parts of the said follower.

In testimony whereof we affix our signatures in presence of two witnesses.
